MECHANISM FOR GRAVITY HANDLING OF BULK MATERIAL

John C. Gifford, Ashtabula, Ohio

Application February 8, 1932, Serial No. 591,608

19 Claims. (Cl. 214—45)

This invention relates to apparatus for gravity handling of bulk material, particularly materials which by reason of brittleness, fragility, or bruising are subject to injury, and has for its object the provision of mechanism to decrease or diminish the accidental breaking or bruising of the same (technically termed "degradation") during such handling.

For example it is customary in trans-shipping coal by rail to raise and overturn the entire car at its destination so as to discharge its contents. As a result these contents are subjected to vertical falls of distances varying from two to fifteen feet, and sometimes a series of such falls arrested at each step by collision with a rigid element of steel or wood, and inasmuch as the larger sizes of coal bring substantially higher prices on the market than the finer grades each experience of this nature decreases the value of the product by an amount which may, in the case of the brittle varieties of coal, amount to as much in the average as twenty-five cents to one dollar per ton. The average degradation of prepared coal from the mines to the head of Lake Superior is variously estimated at from sixty cents to one dollar per ton, the average including all varieties of coal and all varieties of handling and transit. The degradation of Pocahontas coal from the mines to Duluth averages approximately half its total value. In all cases it amounts at least to a substantial proportion of the freight rate and is generally higher than the freight rate for several hundred miles of journey. Similar considerations of degradation though different in nature and degree apply to other bulk minerals such as crushed stone employed for railroad ballast, concrete aggregate, and some metallurgical or chemical operations; to certain vegetable products such as corn and sugar beets; and perhaps to other materials.

Accordingly the main object of my invention is the provision of apparatus whereby this degradation can be materially decreased; and while I have illustrated my improvements specifically in connection with a car dumping device and described its utility with special reference to the handling of coal, it will be understood that this is chosen merely for illustrative purposes and not because the invention is limited to this use or to the specific form shown.

Fig. 1 illustrates somewhat diagrammatically a car-dumping and vessel-loading device showing one mode of applying my improvements thereto; Fig. 2 is a vertical sectional view drawn to enlarged scale through a part of the mecha-

nism shown in Fig. 1, illustrating my improvements in full lines and showing the relation of the same to a previously existent structure, the same corresponding to the section line 2—2 of Fig. 4; Fig. 3 is a detail view corresponding to the line 3—3 of Fig. 4; Fig. 4 is a plan view corresponding to the line 4—4 of Fig. 2; Fig. 5 is a sectional view corresponding to the line 5—5 of Figs. 2 and 4; and Figs. 6 and 7 are wiring diagrams.

In order to facilitate an understanding of the principles of my invention and of a preferred mode of constructing and using the same I consider it desirable to describe the construction and operation of a typical transportation device to which my invention is to be applied for which purpose I have chosen a railway car-dumper. Such a device is oftentimes set on the edge of a dock or quay 1 and comprises a tower-like device having upright side elements 2 and 3 defining a vertical slideway in which is movable a cradle 4 which is raised and lowered bodily by means of suitable cables 5 operated from inside the enginehouse 6 and passing over suitable sheaves 7. Suitable counterweights 8 and 9 are attached to this cradle and operated along other slideways. At its lowest position a coal-car (for example) 10 is run on this cradle, suitable clamping devices (not shown) being provided for its secure location; the cradle is hoisted a predetermined height and the car and cradle then inverted as shown in dotted lines in Fig. 1, the contents of the car being thereby ejected onto an inclined receiver 11 called a pan or chute often-times of hopper shape having downwardly converging side walls 12 (see Fig. 4) and having its bottom inclined at such an angle as to convey the coal or other minerals to a desired point of discharge or storage. In Fig. 1 this pan communicates at its lower end with a telescoping vertical chute 13, the lower end of which depends into the hold of a vessel 14 alongside the dock or quay. The downwardly converging sidewalls 12 of the pan or chute reduce the width of the discharge end of the pan down to a size comparable with the inlet of the vertical chute 13. The lower end of the pan is here shown as carrying a chute-operator's house 15 from which the height and inclination of the chute can be controlled by means of the cables 16 and 17 which are connected to the hoisting engines 18 and 19 respectively. The elevation of the pan 11 can also be varied, a very common expedient being to attach the same to a horizontal girder 20 (Fig. 2) vertically movable along that side-member 2 of the

tower to which the cradle is adjacent; and means is provided for inverting the cradle at the desired position relative to this pan such as forming said girder with arms 21 terminating in a horizontal member 22 adapted to engage slots 23 in one side of the cradle 4, so as to arrest the movement of that side of the cradle, while the opposite side continues to rise and thereby perform the overturning motion. During this overturning the side of the car 10 reclines against suitable buffers 24. All the foregoing parts are old and widely used, and are here explained only to facilitate the understanding of the surroundings in which one form of my invention is employed.

15 The burden of a coal car varies from 50 to 110 tons and this entire load is discharged in approximately five seconds which entails imparting rather high velocities to at least some parts of the load with the production of correspondingly violent impacts and it is one object of my invention to soften this impact without substantially impeding or materially slowing the operation of the car-dumper.

According to my invention I equip the element 25 which receives the coal or other breakable products, in this case the pan 11, with a movable baffle member by which the movement of such product can be arrested and regulated so as to reduce or cushion this vertical drop and thereby decrease 30 the degradation. In the present embodiment this baffle consists of a sort of elongated gate 30 pivoted by means of shaft-means 31 to arms 32 projecting from the longitudinal members 33 of a carriage. Traversing transversely the top of the 35 pan 11 are a pair of girders 34 provided with guides 35 (here shown as rollers) by which the rear ends of these longitudinal members 33 are supported and guided. The forward end of this carriage is supported by the shaft-means 31, the 40 ends of which run in slots 36 of guides 37 located one near each side-wall of the pan. The rear ends of these guides may be supported by one of the girders 34 as shown in Fig. 3; the forward ends are here shown as supported by means of 45 uprights 38 secured to the bottom of the pan (see Figs. 3 and 5).

Carried by the girder 34 is a platform 40 on which is mounted a transverse horizontal shaft 41, operatively connected through suitable speed-reducing gearing 42 to an electric-motor 43 and having near each end a toothed pinion 44 meshing with a rack-member 45 which is connected to the shaft-means 31. Operation of the motor 43 in one direction or the other will cause a forward or backward movement of the carriage and baffle.

Mounted on the carriage is a second horizontal transverse shaft 46 connected through speed-reducing gearing 47 to a motor 48 and having near each end a pinion 49 meshing with a rack motor 48 and having near each end a pinion 49 meshing with a rack 50, which is connected to an up-standing lever-arm 51 rigid with the baffle 30. By causing rotation of the motor 48 in one direction or the other, the baffle 30 can be rotated about its pivot 31 as shown in the full and dotted lines in Fig. 2. It will be noted that the racks 45 and 50 are in the construction illustrated located one directly above the other so that one of the same partly hides the other in Fig. 4, but comparison with Figs. 2 and 5 will make the matter plain, and the construction illustrated has certain practical advantages of simplicity.

Slidably mounted on each of the guides 37 is a vertical shield-plate 52, preferably having its upwardly or forwardly facing portion 53 flared out-

wardly, and having its bottom depending nearly to the pan 11. These shield-plates are located one at each end of the baffle 30. In order to prevent over-running of the motors and to hold the parts fixedly in position when not being intentionally operated, I have shown each motor 43 and 48 as equipped with brakes 54 and 54' respectively operatively connected to solenoids 55 and 55' respectively which are so connected in circuit as to become released whenever the corresponding motor is energized, and to arrest and hold the mechanism whenever the circuit is opened.

Assuming that the complete apparatus heretofore described is employed, the preferred mode of operation is as follows: prior to the arrival of a car at the dumping position, the baffle 30 is moved to its forward upright position shown in Fig. 2, as near the top of the pan and edge of the cradle as the particular installation renders expedient, and certainly sufficiently close to prevent the entire car contents from falling out of the same. As a result, only a limited falling movement of the material can occur, and what little cascading does occur after the very first is arrested by contact with a preceding portion of the load. Preferably the arrangement is such that only a limited outfall of the car-contents is possible with the baffle in this position but local conditions sometimes impede the utilization 100 of my principle to its completest extent. Thereupon the motor 43 is energized to retract the racks 45 in a gradual manner, and thereby retracting the baffle 30 which allows a gradual and gentle outfall of the material. The dimensions are preferably so chosen that by the time the baffle reaches the dotted line position shown in Fig. 2, the entire contents of the car will have been discharged. At this point the motor 43 is stopped and the motor 48 is started, which rotates the baffle 30 so as to allow the material to move slowly therewith down the sloping pan. The speed of this movement is reduced in any case by the slant of the pan-bottom which is ordinarily so chosen as to prevent excessive speed 105 and also by the converging sidewalls 12 of the pan which operate both to reduce the effective gradient traveled by a large part of the materials and to cause the last portion of the load to be retarded by contact with the preceding portion 110 which collects at the relatively narrow discharge end of the pan. As soon as the baffle has been moved to its non-obstructing position the motor 48 is stopped, and the motor 43 started in reverse direction so as to restore the carriage to its former 115 position, as shown in Fig. 2, after which the motor 43 is again stopped and the motor 48 is started (assuming the material by this time to have moved out of the way) so as to restore the baffle 30 to upright position ready for a second 120 load.

These operations may obviously be controlled manually, although it is within my invention to render the same automatic. One mode of effecting this is by means of a series of switches connected and wired as indicated diagrammatically in Figs. 6 and 7, wherein Fig. 6 illustrates a desirable type of layout of the general wiring system for the control of an entire mechanism such as above explained, and Fig. 7 is an enlarged 130 diagrammatic view of the arrangements in one of the junction boxes O in Fig. 6. The junction boxes O and P and the motors 43 and 48 are identical in construction and like parts of such devices will hereinafter be referred to by like nu-

80

merals and reference letters, with difference between that the numerals and letters referring to the parts of the junction box P and the motor 48 are primed numerals and letters.

5 43 represents the rack motor, and 48 the rotating motor as before, each having commutators 100 and 100' and field coils 101 and 101', the coils 102 and 102' of the corresponding brakes 55 and 55' being connected in series with the field coil. The armature contacts are connected between terminals *a* and *b* in the junction box O, the field and brake coils between the terminals *c* and *d*, the last named terminal being also connected to a terminal *e* joined to one line-wire 105, also to the mid-terminal *h* of the reversing-circuit 106 and to switch points *i* and *j* inside the box. Other switch points *k* and *l* paired with *i* and *j* respectively are connected to terminal *c*, and cooperating with points *i*, *j*, *k* and *l* are the switch members *m*, *n*, *o* and *p* respectively, *m* being connected to *o* and *p* being connected to *n* by means of insulating fastenings *q*. The switch-unit *m*—*o* is under the influence of a solenoid *r* and the switch-unit *p*—*n* is under the influence of a second solenoid *s*, one end of each solenoid being joined to a terminal *t* of the stop-circuit and their other ends being connected, respectively, to the supplemental contacts *u* and *v* joined to the respective terminals *w* and *x* of the reversing-circuit. Box P is arranged internally exactly like box O.

35 Mounted in position to be engaged by some part of the moving mechanism are switch devices A, B, C, D, E, F, G and H. Switches A, C, D and G are normally open and switches B, E, F and H are normally closed. *y* designates an operating element of any suitable kind projecting from each switch which, upon contact, changes the condition of that switch from that shown in the drawings to the opposite condition, and which, upon release, allows that switch to return to its illustrated condition.

45 Located in one of the control-houses are two switch panels carrying the manually operated switches H, I, J, K, L, and M. Switches H, J, K, and M are normally open, switches I and L are normally closed. The letters "F", "S" and "R" appearing adjacent to these switches are for "forward", "stop", and "reverse" respectively. One pole of switch A is connected by a circuit element 107 to a circuit-element 108 which joins terminal *x* of box O to one of the terminals of switch K. One terminal of the switch D is connected by circuit-element 109 to a circuit element 104 which connects terminal *w* of box O to one terminal of the switch M. The remaining terminals of switches A and D are connected by the circuit element 117 to the mid-wire 106 of the reversing-circuit which is also connected to the remaining poles of switches K and M.

55 One pole of switch B is connected by circuit-element 110 to terminal *t* of box O and the opposite pole of switch B is connected by circuit-element 111, first to switch L and then to one terminal of switch F. The remaining terminal of switch F is connected by circuit-element 112 to terminal *f* of box O.

65 One pole of switch C is connected by circuit-element 113 to terminal *h* of box O which is the middle element of the reversing-circuit. This terminal is also connected to one side of switches G, H and J. The other terminal of switch C is

connected by circuit element 114 to terminal *x'* of box P and also to the remaining terminal of switch J. One terminal of each of the switches E and N are connected by a circuit element 115 in series with each other. The other terminal of the switch N is connected and with terminal *t'* of box P and the other terminal of the switch E is connected with switch I and thusly with terminal *f'* of box P, so that the operation of any of these switches E, N or I will open that circuit. The remaining pole of switch G is connected by circuit-element 116 to the terminal *w'* of box P, and also to the remaining terminal of switch H. Terminals *e* and *g* of box O and *c'* and *g'* of box P are connected to main line wires 103 and 105, said line being under the control of master switch Z.

75 The mode of operation of the electrical circuits is as follows: we start with the carriage in its uppermost position, and the baffle in obstructing position exactly as shown in Fig. 2; the switches all as shown in Figs. 6 and 7 except a master switch Z which is closed. In order to start the mechanism the attendant closes switch K by pressing the button marked "F" for "forward". This closes the circuit 103, *e*, *f*, 112, F, 111, L, 111, B, 110, *t*, solenoid *s*, contact *v*, terminal *x*, 108, K, 106, *h*, *g*, line 105. The solenoids cause the switch unit *p*—*n* to move to closed position, and then switch *n* by contact with *v* retains the circuit just established and holds the switch closed. As a consequence current flows through the circuit 103, *e*, *d*, brake coil 102, field coil 101, *c*, contact *l*, switch bar *p*, terminal *a*, armature 100, terminal *b*, switch bar *n*, terminal *j*, terminal *g*, line 105. The consequent movement of the carriage by the motor 43 eventually brings it into contact with the switches B and C. The operation of B breaks the circuit first above described, which de-energizes the solenoid *s* and frees the switch unit *p*—*n* which immediately stops the operation of motor 43 (the same result could have been produced at any time in case of need by actuating switch L). The closing of switch C has the following effect upon the parts in the box P, viz: It establishes a circuit from 105 through *h'*, 113, C, 114, *x'*, *v'*, solenoid *s'*, terminal *t'*, circuit 115 and switches *n*, E, I (in series) to terminal *f'*, terminal *e'* and line 103; this energizes solenoid *s'* of box P which closes the corresponding switch unit *p'*—*n'* and operates the motor 48, thereby swinging the baffle 30 into non-obstructing position, which movement finally brings some part of the same into contact with the switches E and D with the following result: The opening of the former breaks the circuit 115 (as could have been done at any time by means of switch I) which de-energizes the solenoid *s'* and opens the circuit of motor 48. The closing of switch D permits the flow of a current in box O from the main 105 through *g*, *h*, *j*, 106, 117, D, 109, 104, *w*, solenoid *r*, terminal *t*, circuit 110, switches B, L, and F in series, circuit 112, *f*, *e* and line 103. This thereupon moves the switch unit *m*—*o* to closed position and operates motor 43 in the reverse direction, thereby restoring the carriage to its original position, whereupon contact is made with the switches F and G. The switch F opens the circuit through *f* and to which de-energizes the solenoid *r* and allows the corresponding switch to open thereupon arresting motor 43 (which could have been done at any time by pressing the button L); while closing of the switch G establishes a circuit through the solenoid *r'* of box P thereby actuating motor 48 in the reverse direction which restores the baffle to 150

80 100 105 110 115 120 125 130 135 140 145 150

85 90 95 100 105 110 115 120 125 130 135 140 145 150

its original position, whereupon said baffle simultaneously engages switches A and N. The consequent opening of the circuit at N arrests the motion of the motor 48 by de-energizing the solenoid r' in box P (which might have been done at any time by pressing the button I); while the closing of switch A has exactly the same effect as did the original closing of switch K, and starts the entire cycle over again. At any instant in the entire cycle any action of any part can be arrested by pressing one of the stop buttons, and either one of the motors can be started in either direction by means of one of the forward or reverse buttons.

15 Presumably it will not always be found necessary to employ this entire circuit, but I suggest this as producing a system which is entirely operative automatically, and wherein the separate elements can be controlled manually at any time.

20 The length of the baffle 30 is preferably made at least the length of the average car; when the check-pieces are flared as shown at 53 they further tend to collect the material, and to compensate for extra long cars or for the erratic

25 placing of the cars in the cradle. When these check-pieces are spaced laterally from the sidewalls of the receiving member or pan they are also spaced longitudinally therefrom to permit any material falling outside the same to pass into the body of the pan. Some pans or receiving members, however, are made with parallel sides in which case these check-pieces can either be omitted or caused to approach closer thereto.

30 It is not necessary in all cases that means be provided to move the baffle bodily forward and back, or that the movement of the baffle into and out of obstructing position be a pivotal movement. Even if the carriage be omitted or locked in a fixed position, a substantial degree of control over

35 the movement of the material can be effected by opening or closing this baffle to a greater or lesser extent. Furthermore it is not necessary that electric-means or even that power-means be employed to operate this baffle or to move the carriage (in cases where such carriage is employed)

40 since any power-source can be employed or even manual labor. The use of my improvements is not limited to boat-loaders or car-dumpers, but can be employed in stone-crushers, mine-tipples, grain-elevators, fruit and vegetable packing establishments, and wherever a cushioned gravity handling of sensitive material is in question.

45 Accordingly it will be understood that many changes in form, shape, mounting, and mode of operation of my essential improvements can be made, and that I do not limit myself to any of the details herein shown or described except as the same are specifically recited in my several 50 claims which I desire may be construed each according to its own limitations and without reference to limitations contained in other claims.

55 Having thus described my invention what I claim is:

60 1. Apparatus for the gravity handling of materials in bulk comprising the combination with an inclined chute of a baffle traversing said chute at a point adjacent to the upper end thereof so as to form a pocket therewith and controllable means for selectively and independently moving said baffle both longitudinally and laterally of said chute for fixing said baffle in selected positions of obstruction and non-obstruction at different predetermined points along and relative to said chute, said means being adapted to

effect the different movements of said baffle independently of each other.

65 2. Apparatus for the gravity handling of materials in bulk comprising the combination with an inclined chute of a baffle traversing said chute at a point near the upper end thereof so as to form a pocket therewith, means whereby said baffle is pivoted upon an axis transverse to said chute, and controllable self-contained power means carried by said chute for rotating and holding said baffle in different angular positions relative to its axis to thereby vary and fix its obstructive effect on the materials in said chute from maximum to substantially zero.

70 3. Apparatus for the gravity handling of materials in bulk comprising the combination with an inclined chute of a baffle transverse to said chute, a support for said baffle, means including a motor for moving said baffle support bodily to different positions longitudinally of said chute, and means including a second motor for moving said baffle with respect to said support for fixing said baffle in different degrees of obstructive position relative to said chute.

75 4. Apparatus for the gravity handling of materials in bulk comprising the combination of a gravity chute, a carriage movable longitudinally of said chute, a baffle operatively attached to said carriage and movable therewith, and means for moving said baffle independently of said carriage to vary its obstructing effect on the materials in said chute at various predetermined points along said chute.

80 5. The combination with a car-dumper and its supporting structure of a vertical chute having an inclined pan communicating with the chute at its upper end and carried at one side of said supporting structure in position to receive and hold substantially the entire car contents upon the dumping thereof and a baffle carried by said pan at a point adjacent to the upper end thereof and defining therewith a compartment for receiving the material discharged from the car and self-contained power means carried by said pan for moving said baffle both longitudinally and laterally of said pan whereby the materials may be quickly discharged from the car onto said pan and then fed to said chute at a relatively slower rate.

85 6. The combination with a car-dumper of a relatively narrow chute having a communicating inclined pan with downwardly converging side walls mounted at its upper end to receive and hold substantially the entire car contents in the upper end thereof and a movable baffle plate carried by said pan at a point a short distance from the upper end thereof, and means to move and fix said baffle plate in positions of varied obstructing and non-obstructing effect within said pan only whereby to first control the rate of escape of material from said car and then to regulate the discharge of material from said pan and into said chute.

90 7. The combination with a car-dumper of an inclined pan with downwardly converging side walls mounted to receive and hold substantially the entire car contents in the upper end thereof and a baffle element traversing said pan, means for moving said baffle element toward and from said pan whereby to regulate its obstructing effect, and means for also moving said baffle element longitudinally of said pan along the upper portion only thereof to control the initial movement of material out of the car and down the portion of said pan traversed by said baffle.

8. The combination with a car-dumper of an inclined pan with downwardly converging side walls spaced from each other at their upper ends to a width at least as great as the length of the car mounted to receive the car contents and a carriage movable lengthwise of the upper end portion of the pan, a baffle element movable with said carriage and also movable relatively to said carriage, power means for controllably effecting movement of said carriage to convey the entire car contents in a controlled manner onto the upper end portion of said pan, and means for varying and fixing the position of said baffle relatively to said carriage to then release the materials discharged from the car for free movement down said pan after they have been conveyed part way down said pan in the aforesaid manner, the converging side walls of said pan serving to retard the flow of the materials down the portion 20 of the pan below said baffle. 80
9. In apparatus for the gravity handling of materials in bulk, the combination with a gravity chute adapted to receive such materials at its upper end, of a baffle element mounted in said chute and having two independent movements therein, one longitudinal of said chute for controlling the movement of the materials over a portion of said chute and the other crosswise of said chute for releasing the materials for free movement down said chute, and controllable motor means and associated gearing carried by said chute for selectively moving and fixing the position of said baffle-element along each such path of movement. 90
10. In a car-dumper, the combination with a car cradle, its supporting structure and an inclined downwardly narrowing pan having a width at its upper end at least as great as the length of the car and carried at one side of said supporting structure, of a baffle in said pan at the upper end thereof, means for presenting said baffle at a point opposite to the open top of said car as the same is overturned toward said pan, and means for controlling the movement of said baffle away from said car whereby the escape of the entire car contents onto said pan is quickly effected and the contents of the car are conveyed in a controlled manner part way down said pan whereupon the car-dumper may be operated to replace the empty car with a loaded car and said baffle may be moved laterally away from the bottom of the pan and returned again to its initial position while the materials released by this movement of the baffle have their downward flow retarded by the narrowing width of the pan. 100
11. In apparatus for handling bulk material, the combination with a car-dumper and its supporting structure, of an inclined downwardly narrowing pan carried at one side of said supporting structure and having a width at its upper end at least as great as the length of a car, and means for controllably obstructing the outflow of materials from the car after the same has reached dumping position comprising a baffle carried by said pan and self-contained power means also carried by said pan for bodily moving said baffle down said pan and away from the car whereby the contents of said car may be quickly emptied into said pan and the car-dumper is free to replace the empty car with a loaded car. 110
12. The combination with a car-dumper, its supporting structure and an inclined downwardly narrowing pan having a width at its upper end at least as great as the length of a car and mounted at one side of said supporting structure to receive and hold the entire car contents in its upper end, of power-operated means carried entirely by said pan for first retarding the outflow of material from the car, next easing the material delivered from the car part way down said pan and then releasing the material for free movement down the remainder of said pan after its delivery from the car whereby the empty car can be replaced by a filled-car during such latter movement of the material. 120
13. The combination with a car-dumper and its supporting structure, an inclined pan having a width at its upper end at least as great as the length of a car and mounted at one side of said supporting structure to receive the car contents, of a baffle carried by said pan for first checking the outflow of materials from the car onto said pan and power-operated means carried entirely by said pan for next bodily moving said baffle part way down said pan and away from the car during the car-dumping operation and then moving said baffle laterally away from said pan after the car has been substantially emptied into the upper end of said pan to release the materials in said pan for gravity movement down the remainder of said pan whereby the car-dumper can be operated to replace the empty car with a full car during at least a part of the time required for the handling of the material in said pan, the lower end of said baffle having a relatively restricted discharge opening whereby to retard the flow of materials between said baffle and the discharge end of said pan. 130
14. Apparatus for the gravity handling of materials in bulk comprising the combination of a gravity chute, a carriage movable longitudinally of said chute, power means for effecting the movement of said carriage, a baffle operatively attached to said carriage and movable therewith, power means for moving said baffle independently of said carriage for varying its obstructing effect on the materials in said chute and control means for said power means. 140
15. Apparatus for the gravity handling of materials in bulk comprising the combination of a gravity chute, a carriage movable longitudinally of said chute, power means for effecting the movement of said carriage, a baffle operatively attached to said carriage and movable therewith, power means for moving said baffle independently of said carriage for varying its obstructing effect relative to said chute, control means for initiating the downward longitudinal movement of said carriage and other control means operatively associated with said carriage and baffle for automatically causing the raising of the baffle at the end of the downward movement of said carriage and the restoring of said carriage and said baffle to their original position. 150
16. Apparatus for the gravity handling of materials in bulk comprising, the combination with an inclined chute of a baffle traversing said chute for controlling the gravity flow of materials, means for supporting said baffle for movement toward and away from said chute at different points along its length, and controllable power means for moving and holding said baffle in different positions with respect to the bottom of said chute and independently of its supporting means to thereby vary and fix its obstructive effect to the flow of materials down said chute from maximum to minimum. 160
17. Apparatus for the gravity handling of materials in bulk comprising, the combination with an inclined chute of a baffle traversing said chute

for controlling the gravity flow of materials, means for supporting said baffle for movement toward and away from said chute, and controllable power means comprising a rack operatively connected to said baffle and a power driven pinion in mesh therewith for moving and holding said baffle in different positions with respect to said chute to thereby vary and fix its obstructive effect to the flow of materials down said chute from maximum to minimum.

18. Apparatus for the gravity handling of materials in bulk comprising, the combination with an inclined chute of a baffle traversing said chute for controlling the gravity flow of materials, means for supporting said baffle for independent movements both longitudinally of said chute and toward and away from the bottom of said chute, and independently operable controllable power means for longitudinally and laterally moving and holding said baffle selectively in dif-

ferent positions with respect to said chute to thereby vary and fix its obstructive effect to the flow of materials down said chute from maximum to minimum.

19. Apparatus for the gravity handling of materials in bulk comprising, the combination with an inclined chute of a baffle traversing said chute for controlling the gravity flow of materials, means for supporting said baffle for movement both longitudinally of said chute and toward and away from the bottom of said chute, and controllable power means comprising rack means operatively connected to said baffle and power driven pinion means engaging said rack means for longitudinally and laterally moving and holding said baffle in different positions with respect to said chute to thereby vary and fix its obstructive effect to the flow of materials down said chute from maximum to minimum.
